UNITED STATES PATENT OFFICE

HARVEY L. COLE, OF CHICAGO, ILLINOIS, ASSIGNOR, BY DIRECT AND MESNE ASSIGNMENTS, TO GLEAMTUBE, INC., A CORPORATION OF ILLINOIS

ILLUMINATED SIGN OR ORNAMENTAL DEVICE

Application filed February 25, 1929. Serial No. 342,330.

This invention relates to electric signs, or electrically illuminated ornamental devices. For example, a well known electric sign, or electrically illuminated ornamental device, is one consisting of a glass tube with neon gas therein, or some similar fluid, with terminals or electrodes at the opposite ends of the tube. When properly connected in circuit, the gas becomes luminous, with the well known result.

Generally stated, therefore, the object of the invention is to provide a novel and improved construction which will obviate the necessity of using neon gas, or any other fluid through which the electric current is passed, but which will, when illuminated, produce substantially the same effect, thus simulating in appearance a neon gas electric sign, or ornamental device.

It is also an object to provide certain details and features of construction and combinations tending to increase the general efficiency and desirability of an illuminated sign or ornamental device of this particular character.

To these and other useful ends, the invention consists in matters hereinafter set forth and claimed and shown in the accompanying drawings, in which—

Fig. 1 is a cross section of an illuminated sign, involving the principles of the invention, on line 1—1 of Fig. 2;

Fig. 2 is a longitudinal section on line 2—2 in Fig. 1;

Fig. 3 is a detail sectional view on line 3—3 in Fig. 2;

Fig. 4 is a view similar to Fig. 2, showing a different form of the invention;

Fig. 5 is a vertical transverse section on line 5—5 in Fig. 4;

Fig. 6 is a view similar to Fig. 2, showing a different form of the invention;

Fig. 7 is a vertical transverse section on line 7—7 in Fig. 6;

Fig. 8 is a front elevation, showing a different form of the invention;

Fig. 9 is a detail horizontal section on line 9—9 in Fig. 8;

Figs. 10 and 11 are similar views, showing different forms of the invention;

Fig. 12 is a transverse sectional view, showing a different form of the invention;

Fig. 13 is a front elevation of a letter unit, showing a different form of the invention;

Fig. 14 is a horizontal section on line 14—14 in Fig. 13;

Fig. 15 is a vertical transverse section through the front panel of a sign embodying the principles of the invention, showing a different form of the invention;

Fig. 16 is a horizontal section on line 16—16 in Fig. 15;

Fig. 17 is a view similar to Fig. 13, showing a different form of the invention; and

Fig. 18 is a horizontal section on line 18—18 in Fig. 17.

As thus illustrated, referring to Figs. 1, 2 and 3, the invention comprises a front panel 1 of opaque material, which can be black or any other shade on its outer surface, to provide a suitable background, and which can be a front wall of a box 2, or other suitable enclosure. The glass tubes 3, 4 and 5 are set into this panel, in the manner shown, these tubes being shaped to form letters, or anything else. These tubes have open end portions 6, and assuming, for example, that these tubes are of pure white glass, each tube can be filled with a red, blue, green, yellow, or other colored water or liquid, or even with a pure white liquid. By having the letters separate, each letter can have a different color or shade. It will be seen that each tube, referring to Fig. 9, has a cylindrical rear side that projects into a space back of the panel 1, and has a cylindrical front side that projects from the face of the panel. It is obvious, however, that the tubes in cross section can be of the shape shown in Fig. 10 or

Fig. 11, or of any other shape, but preferably each tube must have a light-collecting rear portion that can collect the light from the lamp or lamps 7 within the box or closure, and must have a light-projecting front portion projecting from the face of the panel. This produces a very brilliant effect and very closely simulates a neon gas sign or ornamental device, but at much less cost or expense, not only in the manufacturing of the

sign or ornamental device, but also in the operation thereof.

In Figs. 4 and 5, the tubes forming letters are connected together by rubber tubes 8, behind the front panel, so that the liquid can be forced in at one end of the signs and in this manner caused to fill all of the letters.

In Figs. 6 and 7, the construction is similar to that shown in Fig. 4, but in this case 10 the connections 9 between the letters are glass and are integral with the tubes forming the letters, these connections 9 being behind the panel.

In Fig. 8, the construction is similar to that 15 shown in Figs. 6 and 7, but in this case the single long glass tube is bent into shape to form script or hand-writing, which latter is commonly used for the said neon, or neon gas, or similar electric signs, thus closely simulating the letter.

In Fig. 12, the construction is similar to that illustrated in Fig. 1, but in this case the lamp 10 is hung above and its light is reflected through the glass tubing 11 by the reflector 12 back of the panel of the sign.

In each case, therefore, it will be seen that 30 glass tubing is provided, bent into shape to form the letters, or figures, or other things, whatever may be desired, depending upon the use to be made of the illuminated sign or other device. Liquid is provided in the tubing, and means are provided to form a background for the tubing, in combination with means behind the tubing and background 35 to illuminate the tubing, so that the latter will be conspicuously and attractively visible at all times, but especially at night, or in a dark place. Of course, the tubing with the liquid therein can be of a color or shade 40 to contrast effectively with the background, even in the daytime, or in some lighted place. The refraction of the light rays passing through the tubing and liquid, regardless of the cross sectional shape of the tubing, 45 as explained, is such that the sign or other device, is readable from almost any angle in front, substantially like the ordinary neon gas electric sign, so that, in order to read the sign, it is not necessary to stand directly in front thereof. The rear projecting sides of the tubes collect the light rays from all directions, and the outer or front projecting sides of the tubes, or tubing, project the light rays not only straight ahead, but also 50 sidewise in substantially all directions, so that the luminosity of the tubes is substantially the same from whatever angle they are viewed. In other words, the light rays are collected from practically all directions, 55 behind the panel, and then dispersed in practically all directions in front of the panel.

By glass tubing, is meant tubing made of glass or any other transparent or translucent material, which may be used satisfactorily for 60 this purpose. The liquid, of course, can be

water or anything else, but if the sign or ornamental device is to be used out-doors, where freezing temperatures occur, then the liquid must be something that would not freeze, very obviously, in order to prevent bursting or breakage of the tubes. Liquids of this kind, which will not freeze, are well known and do not need to be described here. Also, as shown and described, by tubing is meant hollow glass or other material which is cylindrical or polygonal in cross section, so that it will have both a rear projecting side and a front projecting side for collecting and thereafter dispersing the refracted light rays, in the manner described.

In Figs. 13 and 14, the glass tubing 13 is formed with a flange 14, which latter can be used in various ways, as for fastening the tubing in place on or in the panel or other support. This flange can be of any suitable width, and it is obvious that the flange can be of such size and shape that it will constitute the panel, so that a separate panel will not be necessary. Such a flange can be painted or otherwise treated, to make it opaque, if desired.

In Figs. 15 and 16, the glass tubing 15 has its rear side silvered at 16, or otherwise treated, thereby providing the tubing with a rear reflecting surface which will reflect the light out of it. With this arrangement, the electric lamp 17 can be suitably placed above and in front of the sign or ornamental device, so that its light will be reflected downward upon the tubing, thus illuminating the tubing and the colored liquid therein, with the result that the rays of light will be reflected outwardly by the rear mirror surface of the tubing.

In Figs. 17 and 18, the sign is formed by 105 front and rear plates or sheets of glass 18 and 19, sealed at their edges, and formed with outward bulges 20 and 21 on their front and rear surfaces, these bulges being shaped to form letters, or figures, or anything else. The entire space between the two plates or sheets of glass can be filled with a colored liquid, and with the flat spaces between the letters, or figures, covered with 110 paint or otherwise made opaque, the letters, or figures, or other things, will stand out against a dark background, so that the effect will be substantially the same as that produced by the tubing previously described. The bulges 20 and 21, of whatever shape or 115 configuration, will simulate glass tubing, and will produce substantially the same effect.

Even in Figs. 15 and 16, the rear side of the tubing is in the nature of a light-collecting side, as it collects the light rays, and these rays are then refracted and dispersed in different directions by the front side of the tube.

Thus with the construction shown and described, which is illustrative of different 120

forms of the invention, for example, as shown in Figures 1 to 4 inclusive, the panel 1 is quite thin and in this way the tubing 5 projects front and rear from said panel, in such a manner that the rear side of the tubing serves to collect light rays over a wide range of substantially one hundred and over degrees, approximately one hundred eighty degrees, from different directions behind the panel, and the same is substantially true of the dispersion of the light rays by the front portions of the tubing in front of the panel. In this way, the tubing is visible and readable at different angles to the panel, so that a person standing at either side of the sign can read the lettering or other characters and does not have to view the sign at substantially right angles thereto, but to the contrary can view the sign from angles close to the panel. This visibility and readability of the sign or other device, at different angles over a wide range in front of the panel in a sign having glass tubing filled with translucent or transparent liquid, is true of each of the different forms of the invention shown and described, whereby the invention quite effectively simulates a neon gas tube electric sign.

It will be seen that in each case, or in each form of the invention, as illustrated, for example, in Figs. 3, 7, 9, 10, 11, 14, 16 and 18, the arrangement is such that practically the entire diameter of the tubing is visible on the front of the panel, or on the front of the sign or other apparatus. For example, as shown in Fig. 3, the panel 1 and the tubing 4 are of such relative sizes or thicknesses that the panel does not cut off any of the diameter of the tubing, practically, thereby substantially leaving the full diameter of the tubing exposed on the front of the panel. In this way, the criss-cross refractions and reflections are of such character as to fully illuminate and sharply outline the full diameter or size of the tube of the letters or figures or other things, so that from the front of the sign or other device practically or substantially the full width or diameter of the tubing is visible. Moreover, with the line back of the panel, as shown in Fig. 1, for example, the exposure of the full diameter of the tubing enables the criss-cross refractions and reflections to destroy the image of the light, whereby the letters or figures or other things have an even and uniform illumination.

Thus, illuminated characters are provided by the invention, and by characters is meant letters, figures, numerals, or any other things to which it is desired to draw attention by the attractive illumination thereof.

What I claim as my invention is:

1. An illuminated sign or ornamental device comprising glass tubing shaped to form characters, a light-transmitting liquid in said tubing, a panel into which the tubing is set, the panel being of such thickness that the

tubing projects at front and rear thereof, exposing substantially the full diameter of the tubing at both sides of said panel, together with lighting means behind the panel to illuminate the tubing, so that the rear projecting side of the tubing serves to collect light rays over a wide range of substantially one hundred and over degrees from different directions behind the panel, while the front projecting side of the tubing serves to disperse the refracted light rays over a wide range of substantially one hundred and over degrees in different directions in front of the panel, so that criss-cross refractions and reflections destroy the image of the light and serve to fully illuminate and sharply outline substantially the full diameter of the tubing at the front of the panel, whereby the said tubing is visible and readable at different angles to the panel.

2. A structure as specified in claim 1, said tubing being of clear white glass, and said liquid being colored.

3. Instrumentalities for simulating a neon gas or similar electric sign or ornamental device, comprising glass shaped to form characters, with means forming a contrasting background for said characters, a liquid in said characters to provide the desired color or shade therefor, and means for illuminating said characters, said glass having front portions to disperse the light rays over a wide range of substantially one hundred and over degrees in different directions, so that criss-cross refractions and reflections of the light serve to fully illuminate and sharply outline substantially the full contour of said characters and whereby the said sign or device is luminous and readable or visible from different angles.
